UNITED STATES PATENT OFFICE.

IGNAZ REHLE, OF FRANKFORT-ON-THE-MAIN, GERMANY.

INSERTABLE ARCH SUPPORT.

Application filed December 22, 1926, Serial No. 156,310, and in Germany February 23, 1926.

This invention relates to arch supports of the type in which there is employed a plate curved in a longitudinal direction and provided with a side plate whereby the arch of 5 the foot is elastically supported.

In carrying out my invention I reenforce the middle portion of the plate, that is, the portion which comes directly beneath the instep, whereby this portion which is subject 10 to the maximum depression under load is made more resistant than other portions of the plate. Thus, this portion will not be completely flattened and is at all times capable of exerting a corrective effect upon a foot 15 the arch of which has become flattened by disease or overstrain.

The plate in addition to the reenforcing means above referred to is provided with a transverse plate which is inclined upwardly 20 toward the side flap and is resilient so that it is depressed under comparatively light load. To give the desired resistance to the movement of said transverse plate there is provided a curved spring between the main 25 plate and said transverse plate.

In the accompanying drawings I have illustrated one embodiment of my invention. In these drawings:

Fig. 1 is a top plan view, and

20 Figs. 2 and 3 are sections on the lines *a*—*b* and *c*—*d* respectively of Fig. 1, and looking in the direction of the arrows A and B respectively.

The arch support includes a main plate *a* 25 of sheet metal, preferably enclosed in a leather covering or envelope *m*, the outline of which is indicated in dot and dash lines in Fig. 1. The plate has the usual side flap *b* and is curved in a longitudinal direction except that the middle portion *a*¹ which is situated underneath the instep is substantially flat. In order to resist bending of this middle portion *a*¹ there are provided transverse 40 ribs *d* pressed into the metal and preferably extending downwardly. These are transversely disposed at the forward and rear edges of the intermediate portion and stiffen it so that it does not bend under maximum load.

50 Over this middle portion *a*¹ there is a supporting plate *e* secured in place in any suitable manner, as for instance by a rivet *g* adjacent to the edge of the plate opposite to the flap *b*. The plate *e* is inclined upwardly to-

ward the upper edge of the flap and is supported by a curved spring *f*. One end of this spring may be held between the two plates by the rivet *g*. The free end of the spring curves downwardly and bears on the supporting plate *a* adjacent to the base or lower edge of 55 the flap *b*.

Under the action of the load of the body the inclined supporting plate *e* is lowered, and the spring *f* flattened, until the two plates come into contact at the upper edge of the 60 flap. Consequently the instep of the foot is resiliently supported within the limits of the strength of the spring *f* and the upper plate is positively supported by the free edge of the 65 flap when the spring has been compressed to 70 the maximum extent.

The important feature of the invention is the provision of the reenforcing means whereby the part of the plate *a* beneath the inclined plate *e* is prevented from bending under 75 strain. The portions of the main plate *a* in advance of and in the rear of this middle portion, may bend, but the middle portion remains stiff.

Having thus described my invention, what 80 I claim as new and desire to secure by Letters Patent is:

1. An arch support including a main plate curved longitudinally and provided with a side flap and transversely extending stiffening ribs at the front and rear edges of the middle portion of the plate, a transversely extending plate secured to said first mentioned plate above said middle portion, and a spring between said plates for yieldingly 85 supporting said transversely extending plate.

2. An arch support including a main plate curved longitudinally and having an upwardly extending flange at one edge, a transverse plate secured to said first mentioned 95 plate at the edge opposite to said flange, and having a free edge normally spaced above said flange, and a spring between said plates for yieldingly supporting said last mentioned edge of the second mentioned plate, but permitting the latter to be pressed down into engagement with said flange, said main plate having stiffening ribs extending transversely thereof adjacent to the front and rear edges of said second mentioned plate.

In testimony whereof I affix my signature.

IGNAZ REHLE.
